UNITED STATES PATENT OFFICE.

JOSEPH JOSEPH, OF CLEVELAND, OHIO.

POLISHING-WHEEL.

1,080,561.

Specification of Letters Patent.

Patented Dec. 9, 1913.

Application filed September 25, 1913. Serial No. 791,871.

To all whom it may concern:

Be it known that I, JOSEPH JOSEPH, citizen of the United States, residing at Cleveland, in the county of Cuyahoga and State 5 of Ohio, have invented certain new and useful Improvements in Polishing-Wheels, of which the following is a specification.

This invention relates to polishing wheels or blocks suitable for polishing stones or the 10 like having plane surfaces.

The object of the invention is to provide improved means for fastening the polishing stone to a holder or plate which is rotated in the operation of the machine.

15 The invention is illustrated in the accompanying drawing in which—

Figure 1 is a side elevation of the wheel. Fig. 2 is a detail showing one of the claws for holding the stone. Fig. 3 is a bottom 20 view of the wheel. Fig. 4 is a detail in section showing a projection on the top plate for engaging the stone.

Referring specifically to the drawings, 6 indicates a top plate which has on its under 25 side projections or flanges 6^a so located as to engage in the openings or recesses 7 of the stone 8, said openings or recesses being commonly formed in polishing stones. The engagement of the projections 6^a in said openings prevents relative rotation of the plate and the stone and assists in holding the latter in place.

A plurality of removable spring plates or claws 9 are used to hold the stone to the 35 plate. These claws are attached to lugs 12 on the top of the plate by means of bolts 11 the claws being slotted as indicated at 10 to permit adjustment thereof. The bills of

the claws are turned in as indicated at 9^a to engage the stone and the claws are preferably made of spring metal so that when the screws 11 are joined they will bite into the side of the stone 8 with sufficient force to hold the stone in position. By loosening the bolts the stone may be readily attached 45 or detached.

As stated, the flanges 6^a engaging in the holes in the stone prevent relative rotation as the plate is revolved, and the claws hold the stone in position against the underside 50 of the plate.

What I claim as new is:

1. A polishing wheel comprising a stone having openings therein, a plate having projections extending into said openings and 55 engaging the stone, claws attached to the plate and depending beside the stone, and means to press said claws into biting engagement with the sides of the stone, to hold the stone to the plate. 60

2. A polishing wheel comprising a stone having openings in the same, a top plate having projections on its upper and lower sides, the latter extending into the openings and engaging the stone, claws depending below the plate and engaging the periphery of the stone, and fastening devices 65 between said claws and the projections on the upper side of the plate.

In testimony whereof, I do affix my signature in presence of two witnesses.

JOSEPH JOSEPH.
